CLAIM

The ornamental design for a tow tractor, as shown and described.

DESCRIPTION

FIG. 1 is a front, top and left side perspective view of a tow tractor showing my new design;

FIG. 2 is a front, top and right side perspective view thereof; FIG. 3 is a front view thereof;

FIG. 4 is a rear view thereof;

FIG. 5 is a top plan view thereof;

FIG. 6 is a right side view thereof; and,

FIG. 7 is a left side view thereof.

The broken lines depict portions of the tow tractor that form no part of the claimed design.

The bottom plan view is omitted since it is unornamented and forms no part of the claimed design.
